(57) **CLAIM**

The ornamental design for an assembly mountable to locomotive handrailing, as shown and described.

DESCRIPTION

FIG. 1 is a perspective view of an assembly mountable to locomotive handrailing showing our new design according to a first embodiment;

FIG. 2 is another perspective view of the assembly shown in FIG. 1;

FIG. 3 is a front elevation view of the assembly shown in FIG. 1;

FIG. 4 is a back elevation of the assembly shown in FIG. 1;

FIG. 5 is a left side elevation view of the assembly shown in FIG. 1;

FIG. 6 is a right side elevation view of the assembly shown in FIG. 1;

FIG. 7 is a top plan view of the assembly shown in FIG. 1;

FIG. 8 is a bottom plan view of the assembly shown in FIG. 1;

FIG. 9 is a perspective view of an assembly mountable to locomotive handrailing showing our new design according to a second embodiment;

FIG. 10 is another perspective view of the assembly shown in FIG. 9;

FIG. 11 is a front elevation view of the assembly shown in FIG. 9;

FIG. 12 is a back elevation of the assembly shown in FIG. 9;

FIG. 13 is a left side elevation view of the assembly shown in FIG. 9;

(Continued)

FIG. 14 is a right side elevation view of the assembly shown in FIG. 9;
 FIG. 15 is a top plan view of the assembly shown in FIG. 9;
 FIG. 16 is a bottom plan view of the assembly shown in FIG. 9;
 FIG. 17 is a perspective view of an assembly mountable to locomotive handrailing showing our new design according to a third embodiment;
 FIG. 18 is another perspective view of the assembly shown in FIG. 17;
 FIG. 19 is a front elevation view of the assembly shown in FIG. 17;
 FIG. 20 is a back elevation of the assembly shown in FIG. 17;
 FIG. 21 is a left side elevation view of the assembly shown in FIG. 17;
 FIG. 22 is a right side elevation view of the assembly shown in FIG. 17;
 FIG. 23 is a top plan view of the assembly shown in FIG. 17; and,
 FIG. 24 is a bottom plan view of the assembly shown in FIG. 17.

The broken lines shown in the drawings are included for the purpose of illustrating portions of the article that form no part of the claimed design.
